Inventor:
Andreas Stockinger
By his Attorney.

UNITED STATES PATENT OFFICE.

ANDREAS STOCKINGER, OF VIENNA, AUSTRIA-HUNGARY.

DEVICE FOR HOLDING OR RETAINING LADIES' HAIR.

SPECIFICATION forming part of Letters Patent No. 601,418, dated March 29, 1898.

Application filed August 28, 1897. Serial No. 649,850. (No model.) Patented in Hungary January 13, 1895, No. 1,969; in France January 24, 1895, No. 244,594; in England January 25, 1895, No. 1,815; in Austria March 21, 1895, No. 45/957, and in Italy March 31, 1895, LXXIV, 440.

To all whom it may concern:

Be it known that I, ANDREAS STOCKINGER, a subject of the Emperor of Austria, and a resident of the city of Vienna, Austria-Hungary, have invented certain new and useful Improvements in Devices for Holding or Retaining Ladies' Hair, of which the following is a specification.

The invention has been patented in Austria, No. 45/957, dated March 21, 1895; in Hungary, No. 1,969, dated January 13, 1895; in Great Britain, No. 1,815, dated January 25, 1895; in France, No. 244,594, dated January 24, 1895, and in Italy, No. 74/440, dated March 31, 1895.

My invention relates to an improved device for holding or retaining ladies' hair.

In order that my invention may be clearly understood, I will now describe the same with reference to the accompanying drawings, which show various constructional forms of my improved device.

In the drawings, Figure 1 is a side view of the device; Fig. 2, a similar view of a modification; Fig. 3, a side view of a modification in which a fastening-pin is used; Fig. 4, an edge view of Fig. 3, and Fig. 5 a side view of another form of my invention.

My improved device comprises two jaws *a* *a'*, jointed together and having comb-shaped teeth *c* on the sides turned toward each other. Arms *b* are provided either on the jaws themselves, Figs. 1 to 4, or on a ring *A*, carrying the jaws, Fig. 5. The jaws are opened for placing the hair between them. Then they are closed and the lock of hair thus held is wound around the arms *b* in any desired manner. Various means for locking the jaws when closed may be adopted.

In the arrangement shown in Fig. 1 the jaws *a* *a'* are held by a ring or clamp *e*, which is placed over the parts or wings *b* *b'* of the jaws, the said parts *b* *b'* having teeth *d*, with which the ring *e* engages, thereby preventing the accidental opening of the jaws. The said teeth *d* may also be cut obliquely to form parts of a screw-thread, while the ring *e* is provided interiorly with a corresponding female thread, so that the ring may be screwed up and down on the wings.

In the arrangement illustrated in Fig. 2 the jaws are held together by a pin *g*, secured to the hinge or pivot of the jaws and adapted to pass into holes in spring projections *f* *f*, fixed to the wings *b* *b'* of the jaws *a* *a'*, the said spring projections being pressed up to enable the jaws to be opened and thus allowed to spring back onto the pin *g* on closing the jaws. I may also pass a pin *h* through the holes in the projections *f* *f* in order to hold the jaws closed, as shown in Figs. 3 and 4, Fig. 4 being a side elevation of Fig. 3.

The hereinbefore-described locking devices enable the size of the opening between the jaws *a* *a'* to be adjusted at will—for example, by screwing or placing the ring or clamp *e* higher or lower on the parts *b* *b'*, as shown in Fig. 1, or by suitably choosing the holes in the parts *f* *f*, through which the pin *g* or *h* is passed, Fig. 2 or Figs. 3 and 4.

In the arrangement shown in Fig. 5 the locking of the jaws is effected by the wings *b* *b'*, which are arranged at the upper ends of the jaws *a* *a'*, the wings *b* *b'* being elastic or springy and so shaped that they may be caused to engage with each other, as shown.

I claim—

1. In combination, a pair of jaws pivotally connected and having teeth, and having also extensions one of which is hooked about the other, said other extension forming a radial arm about which the hair may be wound, and the arms extending radially from the jaws and in substantially the same plane with said jaws and the teeth thereof, substantially as described.

2. A retaining device for the hair comprising toothed members, a series of arms radially arranged relative to the central portion of the toothed jaws, the said jaws having extensions arranged adjacent to each other to form the clamping means, the said radial arms and extensions presenting a body of substantially circular form, that is in which the ends of the radial arms and extensions are substantially the same distance from the center of the device, substantially as described.

3. A retaining device for the hair comprising toothed members connected together, a series of arms radially arranged relative to

the central portion of the toothed jaws, the said jaws having extensions arranged adjacent to each other and hooked one around the other to form the clamping means, the 5 said radial arms and extensions presenting a body of substantially circular form, that is, in which the ends of the radial arms and extensions are substantially the same distance

from the center of the device, substantially as described.

In testimony whereof I have affixed my signature in presence of two witnesses.

ANDREAS STOCKINGER.

Witnesses:

HARRY BELMONT,
T. G. HARDY.
